UNITED STATES PATENT OFFICE.

HERMANN D. BAUMFALK, OF ESENS, HANOVER, PRUSSIA, GERMANY.

BINDING BOOKS.

SPECIFICATION forming part of Letters Patent No. 240,805, dated May 3, 1881.

Application filed December 9, 1880. (No model.) Patented in Germany September 11, 1878.

To all whom it may concern:

Be it known that I, HERMANN DIEDRICH BAUMFALK, of Esens, Province of Hanover, Prussia, in the Empire of Germany, have invented a new and useful Improvement in Binding Books, (for which I have received German Letters Patent No. 7,392, for fifteen years, dated September 11, 1878,) of which the following is a specification.

10 Figure 1 is a vertical cross-section, showing a book undergoing my improved process of binding. Fig. 2 is a similar view thereof after the back has been rasped or filed. Fig. 3 is a vertical cross-section, showing the process as applied to straight books. Fig. 4 is a similar section of the round-backed book, showing the leaves after they are fastened together by the backing, which is glued thereon. Fig. 5 is an end view of a completely bound book.

15 20 Heretofore books have generally been bound by sewing or stitching the sheets together, and then fastening them suitably within the ordinary covers, or by gluing the sheets to plain fabrics.

25 My invention is designed to do away with such stitching and sewing, and to bind books by a method of gluing the separate leaves upon and felting them together with certain fabric, to which they are all attached, and then fastening them into the outside cover in the ordinary manners.

30 I first take the printed folded sheets, laid on one another in their regular order, and cut them in such a manner that each leaf is separated and disconnected from any other leaf at the back of the book. It is then advisable to mark the cut back with a few pencil-lines. The portion which will form the back of the book, and to which the flexible cloth is to be applied, 35 40 may be distinguished from the cut front without requiring the book-binder to open the book. I then glue or fasten together the six or so outside leaves, on each side of the book, at those edges which will be nearest the back. I then place the leaves in a suitable press or similar holding device, as shown in Fig. 1, where *a a* represent the movable sides of a press, having preferably two iron cheek-pieces, *b b*, and *A* represents the book-leaves to be bound. The 45 50 book-leaves being thus firmly held, I next, with a coarse file or rasp or such suitable instru-

ment, rasp or file the back in the direction of the length of the book-leaves. By this rasping operation the back edges of the leaves are made fibrous or finely subdivided, as indicated 55 at *d* in Fig. 2. Over this rasped back is spread a coating of glue, which thoroughly permeates the divided parts of the leaves, and before this glue is allowed to dry a coating of stronger glue is put on, preferably very hot, and on this 60 coating, while still fresh, is laid a piece, *f*, of cotton flannel or some similar fabric, with its woolly side next the glue. This fabric should be somewhat wider than the back of the book to which it is applied and extend on each side 65 thereof, as shown in Fig. 4. The fibrous face of the cotton flannel enters into intimate connection with the finely-divided parts of the leaves. In fact the two fabrics interlock, the fibrous projections of the paper entering between those of the cotton flannel, ordinarily 70 termed "canton-flannel." This canton or cotton flannel is a fabric having a woolly surface, as is well known.

The description already given applies when 75 the back of the book is rounded, as shown in Figs. 1 and 2. If the book is straight-backed, as shown in Fig. 3, which is the style employed when the book need not open very widely, the leaves *A* are placed between the 80 two movable sides of the press *a a*, which sides are cut away near their tops, so as to leave a wider space there than below, and the leaves *A* put between these sides *a a* are thus allowed to spread more widely at their upper 85 portion, *e*, than below. The book is then rasped in the manner above described, the layer of thin glue spread thereon, and on this layer is placed and pressed cotton wadding or similar substance, upon which the glue is allowed to 90 dry. The cotton wadding adds to the fiber by which the rasped leaves are finally attached to the back of the binding. Upon this surface, when dry, is spread a coating of hot strong glue, and on this the cotton flannel *f*, 95 as heretofore described, is placed, extending slightly beyond the edges of the back. Both the round-back and straight-back books are fastened in their outside covers with the aid of the piece *f*, in the ordinary manner.

100 When the backs of the books are grooved with a saw transversely, in the ordinary man-

ner of book-binders, as is done with thin books, school-books, and the like, the first and last six sheets need not be fastened together in the manner heretofore described. The glue between said last leaves is indicated at *h* in Fig. 5. It serves to insure proper connection of the last leaf with the side *i* of the cover. The advantages of this new process of binding books are that it is cheaper, more rapid, and more convenient than the old method of stitching, and that, nevertheless, books bound in this way are no more liable to come apart than stitched books. There is also a great advantage gained by my method, in that it permits of a more perfect ornamentation of the exposed edges of the leaves. These may, where my process is employed, be ornamented by taking the sections of the book, before the leaves are rasped, as above described, and ornamenting the edges of each section by themselves, and then putting the sections back in their proper position and proceeding with the binding, as described. It is thus possible to have the different sections of leaves ornamented by entirely different processes and with different colors and applications thereof, producing, when the leaves are bound together and

come side by side, novel and beautiful effects, which were impossible by the old method, where the leaves of a book had all to be ornamented at one operation. 30

I am aware that rasped edges of the paper leaves have heretofore been cemented to fabrics. This I do not claim, as it leaves a distinct layer of glue or cement between the fabric of the back and the paper. The glue, when dry, is liable to crack, thus allowing the connection to sever; but by my invention the glue is traversed by the interlocking fibers of the paper and of the woolly cloth. 35 40

I claim—

As a new article of manufacture, a book whose leaves are separated from one another and made fibrous at the back, and whose back strip, *f*, is made of cotton flannel, having its woolly side next to the leaves, so that the fibers of the paper and the flannel are interlocked and felted together, and also united by glue, substantially as specified. 45
